DRAFT CONTROL

Roye W. Franks, Michigan City, Ind.

Application February 7, 1947, Serial No. 727,261

4 Claims. (Cl. 236—45)

1

My invention relates to draft controls for small heaters, water heaters, furnaces, and other combustion chambers and has for its object to provide a new and highly efficient, economically manufactured draft control, in which all of the parts thereof will be quickly and easily made and assembled.

A further object is to provide a draft control which will have the casing so constructed that the vane may be placed therein from the vertical or horizontal sides, enabling the one device to be utilized for vertical pipes, horizontal pipes, or pipes running from the combustion chamber at any angle therebetween.

A still further object is to provide a frame and draft control vane stamped from one piece with the vane reversed and inserted into the opening in the frame by specially designed pivotal means, the frame to be inserted into the draft casing at an angle from the open end, sliding down aligned grooves formed in the draft control casing, the casing being grooved on all four sides so that the frame and vane may be inserted from either of two pairs of aligned grooves, adapting the casing and entire control for use on inclined, vertical or horizontal positions without variation of any of the parts thereof.

A still further object is to provide a draft control having a vane mounted diagonally therein and counterweighted to provide for any amount of draft, the weights to be applied at the factory to meet certain predetermined draft requirements.

A still further object is to provide a draft control having a vane mounted diagonally in the draft casing, the vane to be weighted so that the weight or counterbalance may be adjusted at the time of installation to meet varying requirements of the individual installation, should such be necessary.

In the drawings Figure 1 is a plan view of my draft control.

Figure 2 is a face view of the device, looking into the draft opening.

Figure 3 is a side elevation of Figure 1.

Figure 4 is an edge view of the removable frame and operating vane assembly, showing how it would appear when removed from the device.

Figure 5 is an enlarged vertical section of a part of the casing, showing the position of the frame and vane therein.

Figure 6 is a plan view of a modified type of the device.

Figure 7 is a side elevation of Figure 6.

2

Figure 8 is an enlarged vertical section of the modified frame and vane.

Figure 9 is an end view of Figure 8, showing the vane operating therein.

5 In the drawings in which I have illustrated the preferred embodiment of my invention, I have shown the casing for holding my control as a casing A, as square or rectangular in cross section with the one end cut on two sides in arcuate curves to fit against the side of a flue pipe section B, around an opening cut therefrom and secured thereto by welding or other suitable means. The flue pipe B is formed with one end to fit into the next succeeding section of pipe and the other end to slip over a preceding section.

10 The side walls of the casing A are formed from a single sheet of material formed with slanting grooves 5 extending in from the open end 6 on an incline of approximately forty-five degrees, 15 the grooves 5 being made in pairs, one groove on each sidewall of the casing so that a frame C may be inserted into the casing by sliding the sides down the opposed grooves in the casing. The two alternate sides of the casing A are formed alike so that when desired the framework 20 may be inserted into like pairs of grooves 5 when using the draft control on a horizontal or sloping pipe or flue.

25 Extending down from the grooves 5 near the open end of the casing, there are reinforcing grooves or ribs 7 and extending up from the inner end of the grooves 5 there are like reinforcing ribs 8. These sets of grooves formed on each surface of each side of the casing A enable the manufacturer to make the sides of the casing of thin material, but having sufficient strength due to the grooving or ribbing therein.

30 The frame C for supporting the vane of the device is made of a flat sheet of metal having 35 the central area stamped therefrom forming a rectangular framework with a central large opening therethrough. The two sides 9 and 10 are bent down to form flanges or sidewalls along each edge and the end 11 is bent down likewise 40 to form an end wall, and both the sidewalls and end wall are then bent out to form a three-sided outwardly extended flange around the sides of the frame, which are inserted into the casing A. The two side flanges 12 and 13 of the outwardly 45 bent flange are adapted to be inserted into any two opposed grooves 5 as shown in Figure 5 of the drawings with the end flange 14 adapted to extend down to meet the bottom wall of the casing A to shut off draft around the perimeter 50 of the frame 6, and the outer end of the frame C

is bent upwardly, forming a flange 15 adapted to engage the outer end of the top of the casing A, sealing off draft from that side of the casing. Thus the draft will entirely pass through the opening in the frame C. When such conditions occur, that draft is passing through the casing A. The vane D for controlling the passage of draft or air through the casing is made from the section which is stamped from or cut out of the frame C, and this vane D is rectangular in cross section and is reinforced by stamping ribs 17 around the vane spaced in a short distance from each edge forming a rectangular reinforcing rib entirely around the vane. Bearing supports for the vane are struck from opposite sides of the frame C to form brackets 18 and 19 to receive the stub shafts for supporting the vane. The stub shafts 20 or bearing shafts for the vane are made from phonograph needles or like shafts may be used on large size models. These shafts are secured to the outer underside of the vane by striking spaced apart strips from the opposite sides thereof and after setting the ends of the bearing shafts thereunder gripping the metal down thereon to hold the shafts in place. The ends of the shafts being pointed will not cause friction when engaged against the side flanges 12 and 13 of the frame C, which engagement might occur should the device be set in a flue pipe which would place the entire casing A slightly off from true horizontal or vertical as the case might be.

A predetermined weight W is attached to the top face of the vane D above the bearing or pivotal line and the weight and position of this weight will be figured at the factory to meet the draft conditions for which the device is made.

Some of these drafts may be made with the weight W adjustable by adding or removing thin sheets or strips of metal therefrom or thereto or by providing screws to be used to shift the weight up or down.

In Figures 6, 7, 8 and 9 I have shown a modification of my invention in which the casing A' is shown with reinforcing ribs X formed on all four sides thereof to give added strength and rigidity to the casing A'.

The frame for providing a draft opening through the casing and supporting the draft responsive vane consists of a rectangular framework 25 having the top end 26 turned back into a clamp 27 which clamp is adapted to engage along the top edge of the casing A'.

The bottom of the frame 25 is provided with spaced apart ears or lugs 27 which are adapted to pass through spaced holes 28 in the base of the casing A and be clamped or bent up against the bottom of the casing to lock the framework in position sloping downwardly and inwardly from the top of the outside opening and toward the flue pipe B'. The vane D' is pivotally mounted in the frame by bearing pins 20' in a

manner similar to that shown in Figure 2 and described heretofore. A depression 29 is provided in the face of the vane D' to receive a counterweight if found necessary.

Having thus described my invention, I claim:

1. A draft control device of the class described, comprising a rectangular hollow body having slanting grooves formed in opposite sides thereof, into which grooves a framework may be inserted; a framework for insertion into said grooves comprising a rectangular member having the edges extended as flanges to fit into said groove; and a control vane pivotally mounted in said framework adapted to open and close commensurate with the variation of draft in the flue pipe.

2. A draft control device of the class described comprising a rectangular body having slanting grooves formed in opposite sides thereof inclined on the same angle; a framework for insertion into said grooves comprising a rectangular member having flanges formed along the edges thereof and adapted to fit into said grooves in the rectangular body and a control frame pivotally mounted in said framework adapted to open or close commensurate with the variation of draft through a flue pipe to which the rectangular body is attached.

3. A draft control of the class described comprising a cylindrical section of flue pipe having a rectangular body attached into open connection with slanting grooves formed in opposite sides of said body to permit insertion of a framework either horizontally or vertically as desired; a framework adapted to be inserted into said grooves and a control vane pivotally mounted in said framework and resting when closed at an angle to the rectangular body.

4. A draft control device comprising a hollow rectangular body having pairs of slanting grooves formed in opposite sides thereof; a rectangular framework adapted to be engaged in either pair of opposite grooves depending upon the position and use of the device; and a control vane pivotally mounted in said rectangular framework adapted to close the opening through the framework when no draft is passing through the hollow body.
